UNITED STATES PATENT OFFICE.

JOHN STRONG ANDREWS, OF MILLTOWN, NEW BRUNSWICK, CANADA.

CAR-COUPING.

SPECIFICATION forming part of Letters Patent No. 313,044, dated March 3, 1885.

Application filed November 10, 1884. (No model.)

To all whom it may concern:

Be it known that I, JOHN STRONG ANDREWS, of Milltown, in the county of Charlotte, of the Province of New Brunswick, in 5 the Dominion of Canada, have invented a new and useful Improvement in Railway Car Couplers; and I do hereby declare the same to be described in the following specification and represented in the accompanying drawings, 10 of which—

Figure 1 is a top view, Fig. 2 a side elevation, Fig. 3 a front end view, Fig. 4 a longitudinal section, and Fig. 5 a transverse section, of my improved car-coupler. Fig. 6 is 15 a top view, and Fig. 7 a longitudinal section, of a shackle to operate with such coupler. Fig. 8 is a front elevation of the jaws and their support-piece. Fig. 9 is an under side view of the cam for opening the jaws. Fig. 10 is 20 a vertical and transverse section of one of the jaws and its support-piece; and Fig. 11 is a transverse section of the two jaws, such section showing the manner in which each jaw is beveled to receive the conical head of the 25 shackle.

The nature of my invention is defined in the claims hereinafter presented.

In such drawings, A denotes a draw-bar, having to its bunter or head a a tapering 30 mouth, b. Directly in rear of such mouth, and in a narrow chamber, c, in the draw-bar, there are arranged a pair of curved jaws, B B, and the support-piece C, to which each of such jaws is pivoted. This support-piece is composed of a plate, b, and two flanges, c' c', extending down therefrom parallel to each other, they being at a proper distance apart to receive between them the upper portions of the jaws, through which portions and the flanges 35 40 the pivotal screws d d of the jaws extend and screw into one of the flanges. Each jaw is provided with a spring, e, suitably applied to it and the support-piece, and is for forcing the said jaw toward its fellow. Between the two jaws there is arranged an "S-shaped" cam, 45 f, for moving them asunder, such cam being fixed on the lower end of an upright spindle, g, journaled in the support-piece at its center, and extending above it, and provided 50 with a handle, h, all being as represented. Each jaw is beveled or inclined from its outer

to its inner edge, as shown at i. The support-piece is inserted and fastened within the draw-bar head, and there is directly in rear of such support-piece a cylindrical chamber, 55 k, which, formed in the draw-bar, contains a spiral spring, D, which is to act as a bunter to the shackle-head on its passage between the jaws, and to expel it therefrom on their being opened for discharge of the shackle. In front 60 of the support-piece there is extending down through the head of the draw-bar a hole, m, for reception of a pin, n, to enable the draw-bar, when necessary, to be connected to another adapted to receive a common shackling- 65 link.

The shackle for use with the coupler, as hereinbefore described, has two conical heads, o o, projecting from the smaller ends of the two conically-shaped bodies p p, connected by 70 a chain, r, and having between them, and extending from one to the other, a spiral spring, s, into which, at its ends, the bodies p p are extended, as represented. The ends of the spring rest against shoulders q, formed in the 75 said bodies. Furthermore, there is in each of such bodies a hole, t, which goes diametrically through the body, and is to receive the pin n, when the shackle is connected with the draw-bar by such pin, and not by the jaws. 80 The two bodies of the shackle may be joined by a rigid connection or bar, instead of by yielding ones—viz., the chain and spring, as described; but with these latter the shackle can readily bend laterally should it be borne 85 against one side of the mouth of the draw-bar while the cars may be running on a curve of the railway-track. On the shackle being driven endwise into the head of the draw-bar and between the jaws, it will force them apart 90 and pass between them, after which they will close upon it in advance of the conical head that may have so opened them. In so closing upon the shackle they, with the said head, will couple it to the draw-bar. 95

To set the shackle free, the cam f is to be partially revolved, so as to force the jaws sufficiently apart for the spring D to expel the shackle from the draw-bar, such spring having been contracted by the shackle in its passage into the draw-bar for being coupled therewith. The spring D also serves to aid 100

in supporting the shackle in a horizontal position, in order for it to be properly presented to engage with another draw-bar.

I claim—

- 5 1. The combination of the draw-bar with the separate support-piece C, arranged within it above its chamber, and with the beveled jaws and their closing-springs, and the mechanism for moving such jaws apart, applied to such support-piece, all being substantially as set forth.
- 15 2. The shackle, substantially, and for use with the jawed coupler, as explained, such shackle consisting of the two conically-headed bodies and their connecting-chain and spiral spring, arranged as set forth.
- 15 3. The shackle composed of the two connected conically-headed bodies, provided with holes extending diametrically through them,

such heads and holes being for shackling either of such bodies to a draw-bar by a pin, or by jaws arranged therein, as set forth.

4. The combination of the draw or bunter bar provided with a spiral spring and a narrow chamber, and a tapering mouth in advance thereof, and with a pin - passage extending down through such mouth, as described, with a pair of beveled jaws arranged in such chamber, and having springs for closing them upon a shackle, and also having mechanism, as specified, for opening them for the discharge from them of such shackle, all being substantially as set forth.

JOHN STRONG ANDREWS.
